UNITED STATES PATENT OFFICE.

LOUIS GATHMANN, OF WASHINGTON, DISTRICT OF COLUMBIA, ASSIGNOR OF ONE-
FOURTH TO EMIL GATHMANN, OF BETHLEHEM, PENNSYLVANIA.

AIR-PROPELLER FOR FLYING-MACHINES.

No. 871,926.

Specification of Letters Patent.

Patented Nov. 26, 1907.

Application filed March 6, 1907. Serial No. 360,818.

To all whom it may concern:

Be it known that I, LOUIS GATHMANN, of Washington, in the District of Columbia, have invented a new and useful Improvement 5 in an Air-Propeller for Flying-Machines, of which the following is a specification.

My invention has for its object the production of an air propeller designed to afford 10 a maximum thrusting or lifting efficiency with a minimum application of power. My invention further consists in providing means for using an air propeller in connection with an apparatus adapted for aerial 15 flight.

To this end my invention consists in certain novel features and combination of parts which I will now proceed to briefly describe and particularly point out in the claims.

20 In the accompanying drawings Figure 1 is a plan or top view of an air propeller having two sets of vanes. Fig. 2 is a cross section on line 2—2 of Fig. 1. Fig. 2a shows two propellers mounted on two shafts 12 and 12', the 25 latter being a hollow shaft so that the propellers may be rotated in opposite directions to each other. Fig. 3 is a vertical section of the car of the apparatus.

Similar letters refer to similar parts 30 throughout the several views.

10 is the propeller towards the center of which is located the hub 11 which is securely fastened to the vanes and preferably to the propeller shaft 12.

35 13, 13' and 13'' are the aero-blades or planes, 14 being the forward portion and 15 the rear portion of the same.

16 is the circumferential retaining wall of the vanes.

40 17 is the car of apparatus adapted for aerial flight.

18 and 18' are annular rims which support the main construction of the car.

45 19 is illustrative of motor for rotating the propeller shaft or shafts.

By rotating the propeller thus constructed at a high rate of speed, rarefaction or negative pressure is produced above the said superimposed blades or planes 13, 13' and 50 13'' of the vanes 10. The resulting difference between the pressure upon the upper and lower sides of said aero-planes or blades, gives the propeller a lifting or thrusting force exactly proportional to the degrees of difference of this pressure.

The high efficiency of the propeller thus constructed is due to the following essential parts and the combination of the superimposed aero-blades or planes 13, 13' and 13'' and to the circumferential retaining wall 16. 60 The air at atmospheric pressure entering at the forward portion 14 between the aero-blades or planes, owing to the rotation of the vanes in the direction of the arrows, is forced toward the retaining wall 16 by centrifugal 65 force and is therefore considerably compressed before passing downward from the delivery channels X—X at the rear portion 15 of the aero-blades or planes. As the compressed air is discharged downward from delivery channels X—X it performs its most 70 important function by impacting against the atmosphere the reaction or recoil against the aero-blades, forcing the propeller in the opposite direction from the flow of the escaping 75 air in a manner similar to a rocket.

In order to obtain the maximum recoil or reaction it will be seen that the uppermost aero-plane or blade 13 should extend beyond the rear edge of the lower blade or plane. It 80 is also very important to have the rear edge 15 of the higher aero-plane or blade extend lower than the aero-plane or blade situated below, as shown in section in Fig. 2, so as not to create a rarefaction or rotary motion of 85 the air in front of the aero-plane above and thus produce excessive slip and yielding lower pressure.

Extensive experiments which have extended over a period of a number of years 90 have convinced me that the key to successful flying machines is a propeller of high efficiency. A propeller consisting of rotary aero-planes on the lines shown and described has, from actual tests made by me, shown a 95 lifting force of 75 pounds per applied horse-power. An aerial locomobile with this type of propeller, built entirely of high grade steel, and having 20 feet extreme diameter, weighs approximately 900 pounds and would have 100 a carrying capacity of 2,400 pounds with applied power of 32 horse power.

It is obvious that the principle of my invention may be modified in many ways, for instance, small openings in the wall 16 105 would not affect the result or efficiency materially although a smooth, closed surface is best; also, the propeller may be mounted either horizontally or vertically.

Many modifications may undoubtedly be 110

made without departing from the spirit of my invention.

Having now particularly described and ascertained the nature of my invention and in what manner the same is to be operated, what I claim is:—

1. An air propeller having two or more sets of vanes each of said vanes consisting of two or more superimposed aero-planes, the 10 rear edge of the uppermost aero-plane extending beyond the rear edge of the lower planes.

2. An air propeller having two or more sets of vanes each of said vanes consisting of 15 two or more superimposed aero-planes, the rear edge of the uppermost aero-plane overlapping or extending to rearward and downwardly beyond the rear edge of the underneath plane, substantially as set forth and 20 for the purpose described.

3. A rotary air propeller having two or more sets of vanes each of said vanes consisting of two or more superimposed aero-planes, the outer or peripheral portion of 25 said planes being located in a lower plane than their inner portion.

4. An air propeller having two or more sets of vanes each of said vanes consisting of two or more superimposed aero-planes or 30 blades, the rear edge of the uppermost aero-plane or blade overlapping rearwardly the rear edge of lower planes, and a segmental circumferential wall for closing the passage between said aero-planes or blades.

35 5. An air propeller having two or more sets of vanes each of said vanes consisting of two or more superimposed aero-planes or blades, the rear edge of the uppermost aero-plane or blade overlapping rearwardly the 40 rear edge of lower planes, and a segmental circumferential wall for closing the passage between said aero-planes or blades and having the aero-planes or blades inclining at a downward angle towards their circumfer-
ence.

45 6. An air propeller having two or more

sets of vanes each of said vanes consisting of two or more superimposed aero-planes or blades, the rear edge of the uppermost aero-plane or blade overlapping rearwardly the 50 rear edge of lower planes, and a segmental circumferential wall for closing the passage between said aero-planes or blades and having the aero-planes or blades inclining at a downward angle from the horizontal to- 55 wards their rear portion and towards the circumference.

7. An air propeller having two or more sets of vanes each of said vanes consisting of two or more superimposed aero-planes, 60 the rear edge of the uppermost aero-plane extending beyond the rear edge of the lower planes, in combination with a car containing motive power for rotating the propellers.

8. An air propeller having two or more sets of vanes each of said vanes consisting of two or more superimposed or adjacent aero-planes, the rear edge of the greater planes 65 extending beyond the rear edge of the lesser planes.

70 9. A rotary air propeller having two or more sets of vanes each of said vanes consisting of two or more superimposed or adjacent aero-planes, said aero-planes having their peripheral portions located in one 75 plane and their inner portions in another plane, substantially as and for the purpose specified.

10. A rotary air propeller having two or more sets of vanes each of said vanes consisting of two or more superimposed or adjacent aero-planes, said aero-planes having their outer or peripheral portion located in a plane other than that on which their inner portion is located, and a segmental circumferential wall for closing the peripheral passages between said aero-planes.
